TRAFFIC REGULATING SYSTEM AND
MECHANISM THEREFOR

William L. James, Long Beach, Calif.

Application February 1, 1932, Serial No. 590,119

3 Claims. (Cl. 177—337)

This invention relates to traffic regulation systems and mechanism therefor.

The general object of the invention is to provide an improved signal device.

3 A more specific object of my invention is to provide a novel vehicle operated traffic signal.

A further object of the invention is to provide a novel mechanism for actuation of vehicle signals.

10 An additional object of the invention is to provide a novel vehicle actuated signal mechanism.

A further object of the invention is to provide a novel signal control mechanism wherein novel means is provided for changing the length of time 15 of operation of the signal.

Other objects and advantages of this invention will be apparent from the following description, taken in connection with the accompanying drawings, wherein:

20 Fig. 1 is a perspective view of a street intersection showing two of my improved traffic regulating devices operatively installed.

Fig. 2 is a horizontal section through a control box showing a top plan view of my improved control mechanism.

25 Fig. 3 is a section taken on line 3—3 of Fig. 2.

Fig. 4 is a fragmentary section taken on line 4—4 of Fig. 2, showing a side elevation of my improved control mechanism with parts thereof in 30 section.

Fig. 5 is an enlarged fragmentary section taken on line 5—5 of Fig. 2.

Fig. 6 is a section taken on line 6—6 of Fig. 5.

35 Fig. 7 is a fragmentary view of the yoke used opposite the one shown in Fig. 6 showing the release cam and latch mechanism associated therewith.

Fig. 8 is a fragmentary view similar to Fig. 6 showing the parts thereof in a different position.

40 Fig. 9 is a fragmentary section taken on line 9—9 of Fig. 5.

Fig. 10 is a fragmentary section taken on line 10—10 of Fig. 5 with parts broken away to more clearly show various elements.

45 Fig. 11 is a detail of one of the members shown in Fig. 10.

Fig. 12 is a fragmentary section taken on line 12—12 of Fig. 6.

Fig. 13 is a fragmentary view of one of the yoke 50 members showing the gear plunger latch mechanism in a different position from that shown in Fig. 5.

Fig. 14 is a section taken on line 14—14 of Fig. 13.

55 Fig. 15 is a section taken on line 15—15 of Fig. 5.

Fig. 16 is a view of the portion of the yoke shown in Fig. 14, showing the device engaging the lower stop block.

Fig. 17 is a view of the portion of the yoke shown in Fig. 15, showing it in the same position as the device shown in Fig. 16.

Fig. 18 is a fragmentary sectional view across a street showing my improved vehicle operated switch mechanism.

Fig. 19 is an enlarged fragmentary longitudinal section showing the switch operating device.

Fig. 20 is a section taken on line 20—20 of the device shown in Fig. 18.

Fig. 21 is a fragmentary end view of the device shown in Fig. 19.

Fig. 22 is an enlarged fragmentary section through the street switch.

Fig. 23 is a section taken on line 23—23 of Fig. 22.

Fig. 24 is a diagrammatic view showing the wiring arrangement of my improved traffic regulating system, and

Fig. 25 is an across-the-line diagram.

My improved traffic regulating system may be used in many ways to meet local requirements 25 and as an example of one use I illustrate it as comprising traffic signals 10 which control traffic in the direction indicated at A, similar signals 12 for controlling traffic in another direction indicated at B, and vehicle operated street 30 switches 13 which are operated by vehicles traveling in the direction controlled by the signals 10 and similar street switches 14 which are operated by vehicles traveling in the directions controlled by the signals 12. The control device for 35 the system is shown as positioned in a housing 15 which is mounted on the post 15' of one of the traffic signals 10.

As shown the signals 10 each include a green light 16, a red light 17 and a bell, buzzer, or other audible signal 18, and the signals 12 each including a green light 19, a red light 20 and a bell, buzzer, or other audible signal 21.

My system further includes pedestrian operated switches 22 which are adapted to be actuated by pedestrians desiring to travel in the A direction and similar switches 23 which are adapted to be actuated by pedestrians desiring to travel in the B direction.

The control mechanism which is positioned in 50 the housing 15 is indicated generally at 25 and includes a base 26 which is secured to a bracket 27 secured to the housing 15. The base 26 includes a pair of spaced upright legs 28 having bearing portions 29 in which anti-friction bear- 55.

ing members 38 are positioned and which support a shaft 31. Positioned intermediate the legs 28 and at one side of the shaft 31 the base is provided with an upright member 32 which supports 5 a platform 33 spaced above the shaft 31.

Secured adjacent one end of the shaft 31 I provide a gear 34 which meshes with a gear 35 which is secured to a shaft 36 of a gear reduction electric motor unit 37. Secured to the shaft 31 10 in spaced relation I provide a gear 38 and a gear 39. Thus it will be apparent that when the motor unit 37 operates the gear 35 will rotate the gear 34 which will in turn rotate the shaft 31 and the shaft will rotate the gears 38 and 39.

15 Mounted loosely on the shaft 31 on one side of the upright member 32 I provide a yoke member 40 which straddles the gear 38 and mounted loosely on the shaft 31 on the opposite side of the upright member 32 I provide a similar yoke member 42 which straddles the gear 39.

20 As the structural details of both the yoke members 40 and 42 are the same I will describe but one of them. As shown the yoke member 40 includes a body portion 43 having a pair of legs 25 44 spaced one on each side of the gear 38, which terminate in bearing portions 45 in which anti-friction bearing members 46 mounted on the shaft 31 are positioned (see Fig. 4). Surrounding the shaft 31 between adjacent bearing portions 45 of the yokes 40 and 42 I provide a spacing sleeve 47.

25 For resiliently urging the yokes to swing about the axis of the shaft 31 in a direction away from the upright member 32 I provide spring members 48 which are shown as being coiled around the sleeve 47 and having one end anchored to the upright member as at 49 and having their other ends secured to a leg 44 of their associated yoke members as at 50.

30 One of the bearing portions 45 of each of the yoke members includes an extension leg 51 having a weighted member 52 thereon which approximately counterweights the weight of the body portion 43 and its associated parts.

35 40 For limiting the downward movement of the yokes I provide for each yoke a stop block 53 (see Figs. 3, 4 and 16). The block 53 is preferably made of fiber and is mounted on a plate 54 which has pins 55 secured thereto which pass 45 through apertures 56 in a plate 57. Surrounding the pins 55 between the plates 54 and 57 I provide coiled springs 58 which urge the plate 54 away from the plate 57 and for limiting the movement of the plate 54 away from the plate 57 50 I secure collars 59 on the pins 55.

55 The plates 57 are mounted on arcuately shaped bars 60 which are mounted in arcuate slots 61 in blocks 62 which are shown as integral with the base 26. For retaining the bars 60 in 60 adjusted positions I provide a set screw 63 in each of the blocks 62.

65 For limiting the movement of the yokes as they move upward I provide for each of the yokes a member indicated generally at 64 (see Figs. 2, 3, 6 and 15). As shown each of the members 64 includes a body portion 65 which is secured to an arm 66 by a screw 67. The arm 67 includes a bearing portion 68 which is loosely mounted on the shaft 31 between the bearing portions 29 70 of the legs 28 the adjacent bearing portion 56 of the yoke with which it is associated. The arm 66 extends below the shaft 31 where it includes an arcuate portion 69 having therein an arcuate elongated aperture 70 (see Fig. 3). Each 75 of the legs are provided with a boss 71 with which

the portions 69 of the arms 66 have sliding engagement. For retaining the arms 66 in an adjusted position I provide in the legs 28 a bolt 73, the shank of which passes through the aperture 70 of the arm 66 and has a washer and nut 74 5 positioned thereon for clamping the portion 69 of the arm 66 to the boss 71 (see Figs. 3 and 4).

The body 64 supports a tubular member 75 which is closed at one end and has mounted therein a tubular member 76 which is closed at the end 10 opposite the member 75. Positioned in the tubular members 75 and 76 I provide a coiled spring 77 which bears against the closed end of each of the members and resiliently urges the member 76 away from the member 75. For restricting the 15 outward movement of the member 76 I secure to the closed end thereof a rod 78 which extends through the coiled spring and out through an aperture in the closed end of the member 75 where a collar 79 is secured thereto.

20 For retaining the yokes in a raised position I provide on the body 43 of each yoke a bar 80 which includes a portion 81 having a beveled face 82 and a straight face 83 which is adapted to be engaged by a latch member 84 (see Figs. 5, 6, 8 and 13). 25

The latch member 84 is pivotally secured to a bolt 85 positioned in an aperture 86 in the platform 33 and includes an enlarged head 87 which is positioned in a recess 88 in the platform 33 (see Figs. 5, 6, 8 and 13). Secured to the platform 33 over 30 the recess 88 and coaxial therewith I provide an electro-magnetic member 90. The head 87 of the bolt 85 is adapted to act as an armature so that when the magnet 90 is energized the head will be attracted to the magnet raising the bolt 85 with 35 it and thereby moving the latch 84 out of engagement with the bar 80 whereupon, if the other yoke is in a raised position, the spring 48 will swing the yoke downward to the stop block 53.

For resiliently urging the bolt downwardly I 40 provide a coiled spring 90' which is positioned in the recess 89 between the magnet and a portion of the head 87.

45 On the upward travel of the yoke when the bolt 35 is down the beveled surface 82 of the bar 80 engages the beveled surface of the latch member 84 and swings it about its pivotal point and passes thereunder whereafter the latch member 84 again swings down and thereafter prevents downward movement of the yoke until the magnet 90 is again 50 energized.

To prevent the release of one yoke before the other yoke has returned to a latched position I provide rods 91 and 92 which are rotatably mounted in bearings 93 supported by the upright 55 member 32 (see Fig. 5).

55 At one end of the rod 91 I provide an angularly bent finger portion 94' while at the opposite end I provide a similar finger 94'', and on the rod 92 I provide similar finger portions 95 and 95'. Surrounding the rod 91 I provide a coiled spring 96, one end of which is secured to one of the bearings 93 and the opposite end of which is secured to the rod 91 and on the rod 92 I provide a similar spring 97. The springs 96 and 97 are adapted to 65 resiliently urge the finger portions of the rods downwardly.

60 Secured to the adjacent faces of each of the yoke members I provide a plate 98 having a cam surface 99 and a latch member 100 which includes 70 an upwardly extending latching boss 101. As shown in Figs. 6 and 7 the cam plate 98 on the yoke member 40 is adjacent the body portion 43 thereof with the latch member 100 abutting the outer face of the cam member, while the latch 75

member 100 on the yoke member 42 is adjacent the body portion thereof with the cam plate 98 abutting the outer face of the latch member.

The finger portion 94 of the rod 91 is, when the yoke member 42 is in a raised position, adapted to be engaged by the cam surface 99 of the cam plate 98 on the yoke 42 (see Fig. 7). When the finger 94 is thus engaged by the cam surface it is retained in a raised position and retains the finger portion 94' at the opposite end of the rod in a similar position wherein it is raised above the path of movement of the latching boss 101 of the latch member 100 on the yoke member 40 (see Fig. 6).

The finger portion 95 of the rod 92 is, when the yoke member 40 is in a raised position, adapted to be engaged by the cam surface 99 of the cam plate 98 on the yoke 40. When the finger 95 is thus engaged it is retained in a raised position and retains the finger portion 95' at the opposite end of the rod in a raised position wherein it is raised above the path of movement of the latching boss 101 of the latch member 100 on the yoke member 42 (see Fig. 7).

Thus it will be apparent that when both the yoke members 40 and 42 are in a raised position both the finger 94' and the finger 95' are not in a position to restrict downward movement of their respective yoke members and both yoke members are free to swing downwardly when the latch members 84 are moved out of the path of the boss 80.

To prevent both of the yoke members 40 and 42 from swinging downwardly should both of the latch members 84 be raised simultaneously, one of the cam surfaces 99 is arranged to allow one of the latching fingers to drop before the other.

From the foregoing it will also be apparent that when one of the yoke members has swung downwardly the latch finger associated with the other yoke member will engage its associated latching boss and prevent the other yoke member from swinging downwardly even though its associated latch 84 is raised.

For retaining the locking bolt 85 in a raised position for a predetermined time I provide a member 102 which is positioned in a recess 103 in the platform 33 and a plunger 104 which is positioned in a recess 105 in the member 102 and in a recess 106 in the platform 33. Also positioned in the recess 105 of the member 102 I provide a coiled spring 107 which is adapted to resiliently urge the plunger 104 upward. The plunger 104 is provided with a notch 108 having a tapered lower shoulder 109.

The bolt 84 is provided intermediate its length with a reduced portion 109. Adjacent the bolt 85 and positioned at right angles thereto I provide a bar 110 which is positioned in a recess 112 in the platform 33. The bar 110 includes a recessed portion 114 in one side thereof and a tapered portion 115 at one end which is adapted to match the tapered shoulder 109 of the plunger 104. The bar 110 is so positioned in relation to the bolt 85 that when the recessed portion 114 of the bar is aligned with the bolt 85 the plunger is free to move but the bar 110 is not. When the bolt 85 moves upward to a position wherein the reduced portion 109 thereof aligns with the bar 110 the bar is free to move and if moved prevents movement of the bolt 85.

The end of the recess 112 opposite the tapered portion 115 of the bar 110 is shown as closed by a threaded plug 116 and between the plug and the adjacent end of the bar 110 I provide a coiled

spring 117 which resiliently urges the bar 110 into engagement with the plunger 104. Normally the tapered end of the bar 110 is positioned in the notch 108 of the plunger 104 and the recessed portion 114 of the bar 110 aligns with the bolt 85.

The member 102 is adapted to be engaged by an arm 118 which is arcuate and which passes through a slot 119 in a post 119'. A removable pin 120 passes through an aperture 121 to slackly pivot the arm. The post 119' is positioned to the rear of the yoke member and is suitably secured to the platform 33. The arm 118 extends towards the front of the device a predetermined distance and includes a plurality of the apertures 121' whereby the pivoted point of the arm may be changed. A flat spring member 122 secured to the platform 33 engages the arm 118 at the rear of the post 119' and resiliently urges the forward portion of the arm upward. The under side of the arm 118 is adapted to be engaged by a portion 123 of the bar 80 on the yoke member.

When the yoke members are in a raised and locked position each of the bars 110 is in a position wherein the recesses 114 thereof align with their associated bolts 85 and the tapered end of the bars 110 are positioned in the notches 108 of their associated plungers 104. Each of the members 102 is retained in a raised position by their associated arms 118 thus compressing the springs 107.

When one of the magnets 90 is momentarily energized and moves its associated bolt 85 upward to release its associated yoke member, the spring 107 will, when the reduced portion 109 of the bolt 85 aligns with the bar 110, force the plunger 104 upward which in turn, due to the coacting tapered surfaces 109' and 115, will move the bar 110 rearwardly against the action of the spring 112. As the bar 110 is thus moved the recessed portion 114 thereof moves out of alignment with the bolt 85 thereby locking the bolt 85 in a raised position. The bolt 85 is retained in this locked position until the portion 123 of the bar 80 moves out of engagement with the arm 118 as it swings downwardly whereupon the member 102 moves downwardly relieving the excess pressure on the spring 107. As the excess pressure on the spring 107 is released the spring 117 forces the bar 110 forwardly and the plunger 104 downwardly through the medium of the tapered surfaces 109' and 115. When the bar 110 is again in a full forward position the recessed portion 114 thereof again aligns with the bolt 85 and the spring 90' moves the bolt 85 downwardly to its initial position wherein it will lock the yoke in a raised position when the yoke returns to its initial raised position.

When one of the yoke members, such as the yoke 40, has been released and has swung downwardly and the magnet 90 associated with the yoke member 42 is momentarily energized the plunger 104 associated with the yoke 42 will force the bar 110 rearwardly when the reduced portion 109 of the bolt 85 aligns with the bar and the bar 110 will retain the bolt 85 in a raised position.

As previously described the yoke member 42 will remain in a raised position even though the bolt 85 is raised, being locked in a raised position by the finger 95'. When the yoke 40 returns to its initial raised position and the cam surface 99 thereon rocks the rod 95 and swings the finger 95' above the latching boss 101 the yoke member 42 will swing downwardly whereupon the bolt 85 associated with the yoke 42 will return to its initial position when the portion 75

123 of the bar 80 moves out of engagement with the arm 118 as previously described.

To return the yoke members 40 and 42 to their initial upright positions when they have swung downwardly I provide on each of the yokes a gripping plunger 125. The gripping plunger 125 is positioned in an aperture 126 in the body 43 and includes an enlarged head 127 which is positioned in a recess 128 in the body 43. Secured 5 to the body 43 coaxial with the recess 128 I provide an electro-magnetic member 129. The head 127 of the plunger 125 is adapted to act as an armature so that when the magnet 129 is energized the head will be attracted to the magnet 10 and raise the plunger 125.

For resiliently urging the gripping plunger 125 downward I provide a coiled spring 130 which is positioned in the recess 128 between the magnet 129 and a portion of the head 127.

20 The lower end of the gripping plunger 125 includes a plurality of prong portions 131 which are adapted to fit between the teeth of the gear 38 or 39 depending on which of these two gears it is associated with. Adjacent the lower end of the gripping plunger 125 I provide a reduced section 132 and adjacent the head 127 I provide a reduced section 133.

25 For retaining the gripping plunger 125 in a raised position I provide a bar 133 which is positioned in an aperture 134 arranged at right angles to the axis of the plunger 125. The bar 133 includes an enlarged head 135 which is positioned in a recess 133 and intermediate the length of the bar 133 I provide a reduced section 137. The end of the recess 136 is shown as closed by a threaded plug 138 and positioned in the recess 136 by a threaded plug 136 and the head 135 of the bar I provide a coiled spring 139 which resiliently urges the bar 133 forwardly. The bar 133 is so positioned with relation to the gripping plunger 125 that when the plunger 125 is in a raised position the spring 139 urges the bar 133 forwardly so that the body portion of the bar 133 lays in the lower reduced section 132 of the gripping plunger 40 and locks the gripping plunger in a raised position. When the bar 133 is in a forward position the forward end thereof projects outward beyond the face of the yoke body 43. As the yoke member swings downwardly the projecting 45 end of the bar 133 strikes the stop block 53 and is forced rearwardly against the action of the spring 139. When the bar 133 is thus moved rearwardly the reduced section 137 thereof aligns with the gripping plunger 125 whereupon the spring 130 forces the gripping plunger downward.

50 As the gripping plunger moves downward the prongs 131 on the lower end thereof engage the teeth of either the gear 38 or 39, depending upon which gear it is associated with and as the gear is rotating at this time it carries the yoke upward towards its initial position. When the yoke member reaches its initial upright position the magnet 129 is momentarily energized whereupon the gripping plunger 125 is raised and the spring 139 55 again forces the bar 133 forwardly when the reduced section 132 of the plunger aligns with the bar 133 thereby again locking the gripping plunger in a raised position.

55 For locking the gripping plunger 125 in a lowered position I provide a bar 140 which is arranged at right angles to the axis of both the gripping plunger and the bar 133 and is positioned in an aperture 141 provided in the base 43. The aperture 141 communicates with an enlarged 60 recess 142 provided in the base 43 which communica-

cates with a further enlarged recess 143 also provided in the base 43. Positioned in the recess 143 I provide a plunger 144 which includes an enlarged head 145. The plunger 144 further includes a coaxial recess 146 and a reduced section 147.

65 One end of the bar 140 is positioned in the plunger 144 and surrounding the bar 140 adjacent the plunger 146 I provide a coiled spring 148. One end of the spring 148 is secured to the bar 140 while the opposite end of the spring is secured to the plunger 144.

70 Secured to the base 43 coaxial with and over the recess 143 I provide an electro-magnetic member 149. The head 145 of the plunger 144 is 15 adapted to act as an armature so that when the magnet 149 is energized the head 145 will be attracted towards the magnet 149 and move the plunger 144 towards the magnet. For resiliently urging the plunger 144 to an extended position 20 away from the magnet 149 I provide a coiled spring 150 which is positioned in the recess 143 between the magnet and a portion of the head 145.

75 The bar 140 includes a reduced section 151 which normally aligns with the gripping plunger 125 and allows free movement thereof. When the gripping plunger 125 is in a lowered position and the magnet 149 is energized the plunger 144 and the bar 140 move towards the magnet 149 30 and a portion of the body of the bar 140 lays in the upper reduced section 132' of the gripping plunger 125 thereby locking the gripping plunger in a lowered position.

80 For retaining the plunger 144 in a retracted 35 position I provide a bar 152 which is arranged at right angles to the plunger 144 and is positioned in an aperture 153 provided in the base 43 which communicates with an enlarged recess 154 also provided in the base 43. Intermediate the length 40 of the bar 152 I provide a reduced section 155 and at one end of the bar I provide an enlarged head 156 which is positioned in the recess 154. The end of the recess 154 is closed by a threaded plug 157 and positioned in the recess 154 between the plug 157 and the head 156 I provide a coiled spring 45 158 which resiliently urges the bar 152 rearwardly.

85 Normally the plunger 144 is in an extended position and the reduced section 155 of the bar 152 aligns therewith and allows free movement 50 of the plunger 144. When the yoke member is swung downward and the magnet 149 moves the plunger 144 to a retracted position the reduced section 147 of the plunger 144 aligns with the bar 152 whereupon the spring 158 forces the bar 152 55 rearwardly so that a portion of the body of the bar lays in the reduced section 147 of the plunger 144 and locks the plunger 144 in a retracted position. When the bar 152 is moved rearwardly the rear end thereof extends out beyond the rear face 60 of the body 43.

90 As the yoke member moves upwardly and approaches its initial upright position the rear end of the bar 152 engages the plunger 76 of the stop member 64 and is held against the action of the spring 158. Whereupon as the yoke member continues to move, the reduced section 155 of the bar 152 is moved into alignment with the plunger 144 whereupon the spring 150 moves the plunger 144 and the rod 140 to an extended position wherein 70 the reduced section 151 of the rod 140 aligns with the gripping plunger 125 and the gripping plunger is free to move upward when the magnet 129 is energized.

95 For actuating the signal lights, buzzers and for 75

energizing the magnets 129 when the yoke members reach their upright position I provide for association with the yoke member 40 a pair of mercury switches 160 and 161 and for association 5 with the yoke member 42 a similar pair of switches 162 and 163.

Each pair of switches is mounted on a bracket 164 which includes trunnions 165 pivotally mounted in bearing members 166 on the platform 33. 10 One of the trunnions 165 of each pair extends outward beyond the face of the adjacent outer bearing member and has secured thereto an operating member 167 which includes a pair of angularly arranged legs 168 and 169. A coiled spring 170 secured to the leg 168 and anchored to a portion of the outer bearing member is arranged to throw the operating member 167 over the center in the same direction in which it is moving when one of the legs is moved a predetermined 20 distance.

For moving the legs 168 and 169 I provide on each of the yoke members a bracket 172 having a roller 173 pivotally mounted thereon which is adapted to engage the legs 168 and 169.

25 When a yoke member is released and swings downwardly the roller 173 swings the leg 168 upward until the leg 168 passes the center line of the spring 170 whereupon the spring snaps the leg past the center and swings the leg upward against a stop 174 provided on the outer bearing member 166. As the operating member is thus moved it rocks its associated mercury switches from one angular position to another and as they are so rocked they make contacts which start 30 the motor 37 and change the signal lights controlled thereby from red to green.

When the yoke member is traveling upward and approaches its initial position the roller 173 engages the leg 169 and swings it rearwardly 40 until the leg 168 passes the center line of the spring 170 whereupon the spring snaps the leg 168 past the center of the spring and moves it downwardly and rearwardly into engagement with the roller 173. The leg 169 is so arranged 45 that on this return movement of the yoke member the leg 168 is snapped over the center line of the spring at approximately the same time the yoke member reaches its initial upright position. As the operating member 167 is rocked on a 50 return of the yoke the mercury switches associated therewith are rocked from their last mentioned angular position to their initial angular position and when thus rocked break the circuit to the motor 37, change their associated lights 55 from green to red, make contacts which operate the buzzers and contacts which momentarily energize the magnet 129 on the yoke member with which it is associated.

As shown in Fig. 24 the mercury switches 160 and 162 are provided intermediate their length with three contacts 175, 176 and 177 which are arranged so that when the switches are in either of their two extreme angular positions the mercury in the switches will not make contact between the three contacts but will make momentary contact therebetween as the switches are being rocked from one position to another. At one end of the switches 160 and 162 I provide a 60 pair of contacts 178 and 179 and at the opposite end I provide a pair of contacts 180 and 181. In the normal inoperative position of the device the contacts 178 and 179 are bridged by the mercury in the switches while the contacts 180 and 181 65 are not so bridged.

At one end of the switches 161 and 163 I provide a pair of contacts 182 and 183 which in the normal inoperative position of the device are not bridged by the mercury in the switches.

Located in the control housing 15 I provide a pair of two way knife switches 185 and 186. As shown the switch 185 includes a pair of spaced terminals 187 and 188 having at one side thereof a pair of spaced contacts 189 and 190 and to the opposite side thereof a pair of spaced contacts 191 and 192. Pivotally secured to the terminal 187 I provide a contact bar 193 and similarly secured to the terminal 188 I provide a contact bar 194. The contact bars 193 and 194 are connected for simultaneous movement by an insulated bar 195.

The switch 186 includes a pair of spaced terminals 196 and 197 having to one side thereof a pair of spaced contacts 198 and 199 and to the opposite side a pair of spaced contacts 200 and 201. Pivotally secured to the terminal 196 I provide a contact bar 202 and pivotally connected to the terminal 197 I provide a similar contact bar 203 both of which are connected together for simultaneous movement by an insulated bar 204.

The vehicle operated switch devices 13 and 14 which are shown as causing actuation of the control mechanism 25 are all of similar construction, therefore but one of these will be described in detail. As shown the switch device 13 includes a raised housing 205 which is positioned adjacent the street curbing a predetermined distance from the street intersections. Positioned in the housing 205 I provide a closed container 206 which includes a horizontal conduit 207 having a vertical conduit 208 communicating therewith which communicates with a vertical cylinder 209. Pivotally mounted in the housing 206 above the cylinder I provide a mercury switch 210 which includes a trunnion 212. Secured to the trunnion 212 I provide an arm 213 which is slackly connected as at 214 to a rod 215 which is secured to a piston 216 mounted for vertical movement in the cylinder 209. The switch 210 and the arm 213 are normally inclined and are adapted to be resiliently retained in this inclined position by a coiled spring 217 having one end secured to the arm 213 and the opposite end anchored to a portion of the housing 206. At the end of the switch 210 which is normally the raised end I provide three spaced contact members 218, 219 and 220.

Embedded in the roadway adjacent the housing 205 I provide a housing 221, the upper end of which is open and level with the surface of the roadway. Positioned in the housing 221 I provide a casing 222 which is preferably made of a good grade of rubber and is resilient. The top of the casing 222 is preferably arcuate in cross section and with the high point thereof spaced above the surface of the roadway. The casing 222 includes a longitudinally extending recess 223 in which a closed inner tubing 224 is positioned. The tubing 224 is preferably made of a good grade of rubber and at one end of the tubing I provide a conduit member 225 which communicates with the interior of the tubing and extends out through a plug 226 in the end of the casing 222 where it is secured to a coupling member 227 by threaded engagement therewith.

The coupling member 227 is positioned in an aperture 228 in the end of the housing 221 adjacent the curb and has connected thereto by threaded engagement one end of a conduit 229. The opposite end of the conduit 229 is suitably secured to the container 206 as by threaded en-

gagement therewith and communicates with the interior of the conduit 207 of the container.

The inner tubing 224, the conduit 229 and the container 206 is filled with liquid up to the level indicated at C in Fig. 22. The liquid used is preferably glycerin or some other suitable fluid which does not become solid at ordinary temperatures.

To allow for expansion and contraction of the fluid in the street switch device I provide a tapered aperture 207' in the conduit 207 and for controlling the passageway through the aperture 207' I provide a needle valve 207".

In operation when the wheel (or wheels) of a vehicle runs over the casing 222 the top of the casing is pushed downward thereby compressing the inner tubing 224 and forcing the fluid to move out of the tubing and through the conduit 229 to the cylinder 209 and upward in the cylinder. As the fluid moves upward in the cylinder 209 it forces the piston 216 upward which through the medium of the rod 215 and the arm 213 rocks the switch 210 to the position indicated by the dotted lines in Fig. 23. When the switch 210 is in this position the mercury in the switch bridges the contacts 218, 219 and 220 and starts the actuation of the control device 25.

After the vehicle has passed over the casing 222 it resumes its normal shape and the fluid displaced from the inner tubing 224 flows back into the tubing thereby lowering the fluid level in the cylinder 209 whereupon the spring 217 rocks the switch 210 to its initial position thereby unbridging the contacts 218, 219 and 220.

The pedestrian operated switches 22A and 23-B are all similar in construction so but one of them will be described in detail.

In Fig. 1 I have shown some of the pedestrian switches 22 and 23 as mounted on the housing 15 of the control device and others as mounted on the standards supporting the traffic regulating devices 12. It will be understood however, that they may be located wherever desired. As shown in Fig. 2 the switch device 22 includes a housing 230 which is secured to the housing 15 and includes a cover 231 which is suitably secured thereto.

Mounted on the housing 230 I provide a block of insulating material 232 having thereon three electrical contact members 233, 234 and 235. The contacts 233, 234 and 235 are adapted to be bridged by a contact ring 236 mounted on an insulated member 237 which includes a button portion 238 extending through an aperture in the cover 231. The contact ring 236 is normally retained out of engagement with the contacts by a coiled spring 239.

When a pedestrian desires to operate the signal devices he presses the button 238 inward against the action of the spring 239 thereby moving the contact ring 236 into engagement with the contacts 233, 234 and 235 wherefor the control device 25 begins to actuate.

As diagrammatically shown in Figs. 24 and 25 one side of the motor 37 is connected by a wire 240 to the positive side of a source of electrical energy which is shown as a battery 241. The other side of the motor 37 is connected by a wire 242 to the contact 183 on each of the mercury switches 161 and 163 of the control device 25. The contact 182 of each of the switches 161 and 163 is connected by a wire 243 to a wire 244 which is connected to the negative side of the battery 241. Thus it will be apparent that when the switches 161 and 163 are rocked from their normal to their operative position the mercury there-

in will bridge the contacts 182 and 183 thus completing the circuit from the battery 241 to the motor 37, through the switches and returning to the battery whereupon the motor 37 will operate. One side of the magnets 90 are each connected by a wire 245 to a wire 246 which is in turn connected to the positive wire 248. The opposite side of each of the magnets 90 is connected by a wire 247 to the contact 229 of their associated street switches 13 or 14. The contact 218 of each of the street switches is connected by a wire 248 to the negative wire 244. Thus it will be apparent that when a street switch 13 or 14 is operated to bridge the contacts 218 and 229 current will flow from the battery 241 to the magnet 90 associated with that particular street switch, through the magnet, through the street switch and return to the negative side of the battery thereby energizing the magnet 90.

One side of each of the magnets 129 is connected by a wire 249 to the positive wire 246. The opposite side of the magnets 129 are connected by a wire 250 to the contact 219 of their associated street switches 13 or 14. Thus it will be apparent that when one of the street switches 13 or 14 is actuated to bridge the contacts 218 and 219 current will flow from the battery through the magnet 129 associated with that particular street switch, through the street switch and return to the negative side of the battery thereby energizing the magnet. One side of each of the magnets 149 is connected by a wire 251 to the positive wire 246. The other side of the magnets 149 is connected by a wire 252 to the wire 250 which is connected to the magnet 129 on the opposite yoke member. Thus when the magnet 129 on the yoke member 40 is energized the magnet 149 on the yoke member 42 will be energized and vice versa.

Each of the contacts 175 of the mercury switches 160 and 162 of the device 25 are connected by a wire 253 to the negative wire 244, each of the contacts 180 are connected to the negative wire 244 by a wire 254 and each of the contacts 178 are connected by a wire 255 to the negative wire 244. The contacts 176 of the switches 160 and 162 are connected by a wire 256 to one terminal of the buzzers 18 and 21 and the opposite terminals of the buzzers are connected by a wire 257 which is connected to the positive wire 240. Thus it will be apparent that when the mercury in the switches 160 and 162 bridges the contacts 175 and 176 the buzzers 18 and 21 will operate.

The contacts 177 of each of the mercury switches 160 and 162 are connected by a wire 258 to the wire 250 of their associated magnets 129. Thus it will be apparent that when the mercury in the switches 160 and 162 bridges the contacts 177 and 175 an electrical circuit will be completed from the battery 241 through the magnets 129 thereby energizing the magnets 129.

The contact 179 of the mercury switch 160 is connected by a wire 259 to the contact 190 of the switch 185. The contact 181 of the mercury switch 160 is connected by a wire 261 to the contact 198 of the switch 186. A wire 264 connects the contacts 198 and 200 of the switch 186 to the contact 191 of the switch 185.

The contact 179 of the mercury switch 162 is connected by a wire 262 to the contact 189 of the switch 185 and the mercury switch contact 181 of the mercury switch 162 is connected by a wire 263 to the contact 199 of the switch 186. A wire 260 connects the contact 199 with the contact 75.

192 of the switch 185 and with the contact 201 of the switch 186.

The terminal 187 of the switch 185 is connected by a wire 265 to the red lights 17 which control the traffic in the A direction and the terminal 188 is connected by a wire 266 to the red lights 20 which control the traffic in the B direction.

The terminal 196 of the switch 186 is connected by a wire 267 to the green lights 19 which control traffic in the B direction and the terminal 197 is connected by a wire 268 to the green lights 16 which control traffic in the A direction. All the lights 16, 17, 19 and 20 are connected by a wire 269 to the wire 257.

15 When the switch 185 is in a position to connect the terminal 187 with the contact 191 and connect the terminal 188 with the contact 192 and the switch 186 is in a position to connect the terminal 196 to the contact 200 and the terminal 197 to the contact 201, none of the lights 16, 17, 19 and 20 will be lighted until the device 25 starts to operate.

When the switch 185 is in the position wherein the terminal 187 is connected to the contact 189 and the terminal 188 is connected to the contact 190 and the switch 186 is in the position wherein the terminal 196 is connected to the contact 198 and the terminal 197 is connected to the contact 199, all the red lights 17 and 20 will be lighted.

When all the red lights are lighted and a vehicle approaches the intersection in the A direction and actuates one of the street switches 13 the control device 25 starts to operate. When the street switch 13 is actuated the magnet 90 on the yoke member 42 is energized thereby releasing the yoke whereupon it swings downwardly. As the yoke 42 swings downwardly it rocks the mercury switches 162 and 163 to a position wherein the mercury unbridges the contacts 178 and 179 and bridges the contacts 180, 181, 182 and 183 thereby starting the motor 31 and disconnecting the circuit to the red lights 17 and completing a circuit to the green lights 16. As the mercury in the switch 162 passes from one end to the other it momentarily bridges the contacts 175 and 176 thereby completing a circuit to all the buzzers 18 and 21.

When the bar 133 of the yoke 42 strikes the stop block 53 the plunger 125 is released and engages the gear 39 whereupon the gear 39 swings the yoke 42 upward to its initial position. When the yoke 42 reaches its initial upright position it rocks the mercury switches 162 and 163 back to their initial positions thereby unbridging the contacts 180, 181, 182 and 183 thereby stopping the motor 31, breaking the circuit to the green lights 16 and completing the circuit to the red lights 17. As the mercury of the switch 162 passes from one end to the other it momentarily bridges the contacts 175, 176 and 177. As the contacts 175 and 176 are bridged the buzzers 18 and 21 are actuated and as the contacts 175 and 177 are bridged the magnet 129 is energized whereupon the plunger 125 is moved upward out of engagement with the gear 39 and is retained in a raised position by the bar 133.

If when the yoke 42 is being returned to its initial position by the gear 39 another vehicle actuates one of the street switches 13 the magnet 129 will be momentarily energized thereby moving the plunger 125 out of engagement with the gear 39 whereupon the yoke 42 again swings downward and strikes the stop block 53 and is again swung upward towards its initial position.

If when the yoke member 42 has been released a vehicle traveling in the B direction operates one of the street switches 14 the magnet 90 of the yoke member 40 will be energized and will raise the bolt 85 upward and which will be retained in a raised position by the bar 110. Although the bolt 85 is raised the yoke 40 will not swing downwardly until the yoke member 42 returns to its initial position and rocks the rod 91 to raise the finger 94' thereon out of engagement with the latching boss 101. At the same time the magnet 90 of the yoke member 40 is energized the magnet 149 of the yoke member 42 is energized whereupon the bar 140 locks the plunger 125 in its extended position. Thus even though a vehicle actuates one of the street switches 13 the yoke member 42 will return to its initial position whereupon the rod 91 will be rocked to release the yoke member 40. The yoke member 42 will be retained in its initial position by the finger 95' which will be moved out of engagement with its associated latch boss 101 when the yoke member 40 returns to its initial position whereupon the yoke member 42 will again swing downwardly.

The contacts 233 of the pedestrian switches 22 and 23 are connected by wires 270 to the wire 248 of their associated street switches, the contacts 234 are connected by wires 271 to the contacts 219 of their associated street switches and the contacts 235 are connected by wires 272 to the contacts 220 of their associated street switches.

When the pedestrian switches 22 or 23 are operated the operation of the control device 25 is the same as that which takes place when the street switches 13 or 14 are operated.

Having thus described my invention, what I claim is:

1. In a traffic regulating system having means to indicate a "stop" for interfering traffic lanes and to indicate "go" for interfering traffic lanes one for each lane, a control device for operating said indicators, said control device including a shaft having a pair of spaced gears thereon, means to rotate said shaft, a pair of pivoted members one for each lane, each of said pivoted members being loosely mounted on said shaft and adjacent to a corresponding gear, weighted means to cause one end of said pivoted members to drop when released, means to limit the drop of said members, means to retain each of said pivoted members in a raised position, a pair of switch mechanisms each being adapted to operate said indicators, means on each pivoted member to engage a portion of the corresponding switch to operate the switch when dropped, means actuated by traffic in each lane for rendering the retaining means for the lane in which traffic has caused actuation ineffective so that the said pivoted member corresponding to that lane is released whereby a vehicle traveling in one lane operates said control device to release the retaining means of one of said members and to allow said one member to drop thereby actuating its associated switch to set said "stop" indicator against traffic traveling in the other lane, and means whereby when a member reaches the limit of its drop its associated gear raises it towards its initial position.

2. In a traffic regulating system having means to indicate "stop" for interfering traffic lanes and to indicate "go" for interfering traffic lanes, a control device for operating said indicators, said control device including a shaft having a

pair of pivoted members one for each lane, each of said pivoted members being loosely mounted on said shaft and adjacent to a corresponding gear, weighted means to cause one end of said 5 pivoted members to drop when released, means to limit the drop of the members, means to retain said pivoted members in a raised position, a pair of switch mechanisms each including an operating member mounted adjacent to a corresponding pivoted member, said switch mechanisms being adapted to operate said indicators, means on each pivoted member to engage the operating member of the corresponding switch to operate that switch, means actuated by traffic 10 in each lane for rendering the retaining means for the lane in which traffic has caused actuation ineffective so that the said pivoted member corresponding to that lane is released whereby a vehicle traveling in one lane operates said control device to release said retaining means and to allow one of said members to drop thereby actuating its associated switch to set said "stop" indicator against traffic traveling in the other lane, and means preventing the retaining means of one 15 lane from becoming ineffective while the pivoted 20

member for the other lane is released and until said released member returns to its initial position whereupon said second member may drop thereby actuating its associated switch.

3. In a traffic regulating system having means to indicate "stop" for interfering traffic lanes and to indicate "go" for interfering traffic lanes, a control device for operating said indicators, said control device including one means effective normally for maintaining the signals in a "stop" position when the control is in one condition of operation and other means normally effective when the control is in a second condition of operation to maintain said signals in a non-operative position, said control device including selecting means operable by a vehicle traveling in one lane to operate said control device to indicate "go" in the one lane and "stop" in the other lane and means thereafter operable by a vehicle traveling in said other direction to cause operation of said control device to indicate "stop" in said one lane and "go" in said other lane with the control means selecting either condition. 15 20

WILLIAM L. JAMES. 25
